Patented May 7, 1968

210,927

COMBINED SPOOL AND THREAD HOLDER

Ellen M. Williamson, 1625 Elderslee Road,
Pittsburgh, Pa. 15227

Filed Oct. 12, 1966, Ser. No. 4,250

Term of patent 14 years

(Cl. D3—19)

Fig. 1

Fig. 2

Fig. 3

FIG. 1 is a side perspective view of a combined spool and thread holder showing my new design, the broken line showing of thread being for purposes of illustration only;

FIG. 2 is an end elevational view thereof; and

FIG. 3 is a side elevational view.

The essential features of my design reside in the full line disclosure.

I claim:

The ornamental design for a combined spool and thread holder, substantially as shown and described.
